UNITED STATES PATENT OFFICE.

JAMES OXLEY, OF SHEFFIELD, ENGLAND.

IMPROVED BREAD-CUTTER.

Specification forming part of Letters Patent No. 42,715, dated May 10, 1864.

To all whom it may concern:

Be it known that I, JAMES OXLEY, of Sheffield, in the county of York and Kingdom of Great Britain and Ireland, have invented certain new and useful Improvements in Apparatus for Cutting, Slicing, and Chopping Bread and other Substances; and I hereby declare that the following is a full, clear, and exact description of the same.

This invention relates to a peculiar construction and arrangement of apparatus for cutting, slicing, and chopping bread, cheese, suet, vegetables, tobacco, leather, or any other substance capable of being cut by a knife; and it consists, essentially, in the employment of a knife which is connected at one end with a vibrating lever-handle working on a center fixed to the table or base of the apparatus, while the opposite end of the knife carries a small anti-friction roller or pin which works along an inclined slotted arm or bracket fixed to the rear end of the table or base of the apparatus. By this arrangement a good draw cut is obtained, the knife being made to move both longitudinally and vertically by the combined action of the lever-handle and inclined slot. The loaf or other article or substance to be sliced or chopped is placed upon the table or base of the apparatus and is pushed home against an adjustable gage carried by the lever-handle after each cut, such gage serving to regulate the different thicknesses of slices to be cut. When the use of the gage is not required, it can be turned back or thrown out of action.

Figure 1 of the accompanying drawings represents a perspective view of one arrangement of my improved apparatus drawn to a scale of about half the real size of the smallest size made.

The same letters of reference indicate corresponding parts throughout all the figures.

A is the base of the apparatus; B, the cutting-table; C, the knife, the rear end of which carries a small anti-friction roller or pin, a, which works in a slot, b, in the inclined bracket D, secured to the base of the apparatus. The front end of the knife is jointed at c to the lever-handle E, which works on a fixed center (not shown in the drawings) in the base A. When used as a bread-slicer, a loaf, F, is placed upon the cutting table or board B and held against the side of the up-

right I while it is pressed forward against the gage K. This gage consists of an arm provided with a collar or socket, d, at one end, through which works a screw-spindle, e, carried in a lateral bracket or projection, L, on the side of the lever E. By turning this screw the gage K is made to approach to or recede from the vertical plane of the cutting-edge of the knife, and consequently the thickness of the slice cut off may be regulated at pleasure. The upright I may be made of metal or wood and has a vertical guiding-slot made therein or made in a separate piece of metal, M, as shown in the drawings, secured to the upright I, through and by which slot the knife C works and is guided. A handle may be formed on the top of the piece M, as shown in the drawings, by which the apparatus may be conveniently carried. In some cases a second guide, N, may be employed, consisting of an upright secured firmly to the cutting-board or base and bearing against the side of the knife, thereby steadyng the same when in the act of cutting. By depressing the lever-handle E the knife C is simultaneously depressed and drawn forward, thereby producing a downward and a forward or draw cut and severing the slice from the end of the loaf. The slice so cut is separated or pushed from the end of the loaf by the small projecting bar or rib O, which is attached by pins or otherwise to the outer side of the knife and extends along its entire cutting-portion; or in lieu of this bar or rib O a small incline or wedge may be secured to the side of the knife.

Fig. 2 on Sheet 2 of my drawings represents a side elevation of a modified form of my machine or cutting apparatus provided with a device for feeding the loaf or other substance to be cut regularly along, so as to insure a perfect regularity in the thickness of the slices without the necessity for using a gage. This arrangement of feed apparatus is intended more particularly to be used when cutting very thin slices—such, for example, as slices of bread or meat, &c., for sandwiches—and, although I have shown it as applied to the modified form of cutter illustrated on Sheet 2 of my drawings, it is equally applicable to the cutter, Fig. 1, shown on Sheet 1 of my drawings. When this feed apparatus is used, the gage which is employed in cutting thicker slices may be thrown out of action.

Fig. 3 is a plan of the modified form of cutter and feed apparatus, and Fig. 4 is an elevation of the opposite side to that shown in Fig. 2—that is, looking on the face of the loaf or other substance being cut. In this modification of the cutting apparatus the knife C is jointed at its rear end, a, to a link, D, working on a center or fulcrum, f, in place of sliding along an inclined slot, b, as in the previous arrangement.

The dotted lines show the position of the knife and gage (the latter being shown thrown back out of action) when the cut is completed.

The feeding apparatus consists of a slide, P, of wood or metal having an upright face, Q, against which the loaf, if used as a bread-cutter, is adjusted and held by the claws or hooks R R, hinged or otherwise fixed to the slide, as shown clearly in Fig. 4, where one portion of the loaf F is shown in vertical section. A trough-shaped piece of metal, S, is fitted onto the under side of the slide, its two edges only projecting slightly beyond the surface. An opening is made in the top of the piece S, through which works a pawl, T, connected with a small lever, U, which works on a fixed center, u, in the piece S. This pawl T takes into the teeth of a rack, V, fixed onto the cutting-table B, so that its teeth are nearly flush with the surface thereof, and a groove is left on each side of the rack to receive the projecting sides of the trough-piece S, as shown in Figs. 2 and 3.

W is a handle secured to the slide, which is grasped by the left hand of the operator, while with the right hand he actuates the knife lever E. After each cut the operator with the forefinger of the left hand raises the small lever U, and causes the pawl T to be moved forward, which, being engaged into a tooth of the rack, has the effect of pushing forward the slide and the loaf a certain distance according to the amount of throw given to the pawl, and it is this advance or throw of the pawl T which in reality regulates the greater or less thickness of the slice cut off from the loaf, the pawl being made to take one, two, three, or more teeth at each stroke, as desired.

It is obvious that in lieu of working the pawl by the finger of the operator, as hereinbefore

described, it may be worked by means of a suitable combination of links and levers from the lever E, which actuates the knife. The advantages of this feed apparatus are that thinner slices can be cut than by the gage above described, while at the same time the loaf being secured to the slide, and the slide guided accurately by the grooves or channels on each side of the rack, the face of the loaf will always be presented parallel to the cutting-plane of the knife, and consequently the slices will not be thinner or thicker on one edge than the other, as would be the case were the face of the loaf presented at an angle either vertically or horizontally to the cutting-plane or path of the knife.

I claim—

1. The general constructions, arrangements, and combinations of apparatus for cutting, slicing, chopping, or mincing bread and other substances, substantially as hereinbefore described, and illustrated by the drawings.
2. The combination of a knife blade with a lever and inclined slotted bracket so disposed as to give a downward draw cut, for the purposes hereinbefore described.
3. The combination of a knife with two links or levers, so disposed as to give a downward draw cut, for the purposes hereinbefore described.
4. The combination of an adjustable gage with a lever working or cutting blade, substantially in the manner and for the purpose described.

5. The application and use of the bar or rib O, or its equivalent, combined with the knife C, for separating or clearing the slices when cut, substantially as hereinbefore described.

6. The application and use of an apparatus, constructed substantially as hereinbefore described, for holding the substance to be cut firmly, and moving it forward step by step at right angles to the knife.

In testimony whereof I have signed my name to this specification in the presence of two subscribing witnesses.

JAMES OXLEY.
